DESIGN FOR A COMBINED PENCIL AND THERMOMETER

Joseph G. Lipic, Jr., St. Louis, Mo., assignor to Jos. Lipic Pen Co., St. Louis, Mo., a corporation of Missouri

Application March 30, 1939, Serial No. 83,916

Term of patent 14 years

To all whom it may concern:

Be it known that I, Joseph G. Lipic, Jr., a citizen of the United States of America, residing in the city of St. Louis, State of Missouri, have invented a new, original, and ornamental Design for a Combined Pencil and Thermometer, of which the following is a specification, reference being had to the accompanying drawing, forming a part thereof.

Fig. 1 is a front elevational view of a combined pencil and thermometer showing my new design.

Fig. 2 is a side elevational view; and
Fig. 3 is an end view of the same.

I claim:

The ornamental design for a combined pencil and thermometer, as shown.
